DRAW BOX ROLL WEIGHTING MECHANISM

Albert D. Harmon, Charlotte, N. C., assignor to
 The Terrell Machine Company, Charlotte, N. C.,
 a corporation of North Carolina

Application November 24, 1950, Serial No. 197,427

14 Claims. (Cl. 19—135)

1

This invention relates in general to draw boxes for the drawing of textile fibers and more particularly to draw box roll weighting devices.

It is well known that the degree of pressure applied to the several successive rolls in a draw box, to enable it to lay the fibers parallel and reduce the weight of the strand uniformly, depends on numerous conditions and for best performance should be individually established for each pair of rolls. For example the pressure between a particular pair of rolls to obtain proper grip for controlling the fibers and for preventing the top roll from slipping will depend on such factors as the peripheral speed of the roll, the draft between successive rolls, the bulk of fibers handled by the rolls, and the character of the fibers. A higher roll speed requires more weight because there is a greater tendency to vibrate and thereby produce uneven pressure on the drawing rolls resulting in uneven drawing. A larger bulk of fibers requires heavier weight because it tends to hold the rolls apart and prevent fiber control. Harsh and wiry fibers as in drawing wool need more pressure than soft pliable ones. Also the weighting ratio changes depending on whether both rolls of the pairs are metallic or whether of the common type in which the bottom roll is metallic and the top roll covered with resilient material as leather, rubber, cork, or the like.

It is desirable to be able to make these necessary individual adjustments rapidly, with precision and without undue effort.

The problem of accurate and simple weighting is further complicated especially in the case of common rolls by the fact that the resilient surfaces of the top rolls are very susceptible to injury and require relatively frequent attention involving removal from the machine. Rapid removal and replacement of the top rolls are required to clear the rolls of lap-ups. Removal may also be for purposes of replacement, checking for trueness of surface, or defects such as channeling or flute marks or even for proper storage during periods of machine shut-down. In all such cases it is desirable to readily remove or replace a particular top roll without disturbing the other rolls and their pressure settings or without loss of the established pressure setting for the removed roll.

Substantially effortless and precise adjusting, unweighting and re-weighting means are not only more conducive to accurate adjustment for better operation, but are also very important particularly under present high operating and labor cost conditions in minimizing down-time of the machine during the necessary adjustments.

Because of the relatively cumbersome construction of draw box weighting devices heretofore

2

used, much expensive time-consuming effort has been required in making roll changes and adjustments. For example, heavy weights have often been used to load the top rolls. Besides being so heavy and hard to handle as to require physical strength beyond that of women operators, it is difficult to make fine adjustments of pressure between the rolls with these devices. Also the hooks used for suspending these weights from the top rolls were generally difficult to manipulate in releasing and re-weighting the rolls.

In the instances where springs were used to load the rolls the conditions were not much improved. Separate adjustment at each end of the roll was necessary by trial and error methods for equalizing the pressure at both ends. Relieving the pressure at one pair of rolls for removal and replacement generally necessitated relieving the pressure at all pairs of rolls with the possibility of disturbing individual adjustments.

Pursuant to the present invention, these difficulties are overcome in a draw box which incorporates a novel weighting arrangement which permits attention to and rapid adjustment and replacement of individual pairs of rolls without loss of the preexisting weighting thereof and without in any way disturbing other rolls in the draw box. Also accurate adjustment of pressure between the rolls of a pair at pre-selected known increments is simplified to adjustment at a single point with automatic equalization at both ends of the top roll. Release of a selected roll for easy and rapid removal, if desired, is reduced to a simple nearly effortless single lever action.

The above is achieved in a relatively simple, compact, inexpensive and readily manufacturable embodiment by providing generally a load transmitting or weighting member at each end of a top roll, with a pressure equalizing beam or bar adapted to transmit to both members a spring load imposed at a point on the beam intermediate the two members. The spring load at the beam is provided by fixing one end of a loading rod to the beam at the above intermediate point and compressing a spring surrounding the rod between a stop at the other end of the rod and a fixed abutment formed by an extension of the machine frame between the equalizing beam and the stop. By making the stop in the form of a nut fitting a threaded portion on the end of the loading bar, the degree of compression on the spring and thereby the pressure between the rolls is made adjustable.

Very accurate adjustment of pressure and removal of trial and error loading increment adjustments is achieved by providing calibration marks on the nut so arranged as to use the bottom portion of a cylindrical cover or shield over the spring as a reference. The cylindrical cover

or shield is crimped at both ends to restrict the extension of the spring to a desired maximum length thereby providing a suitable predetermined minimum pressure at the rolls, easy assembly of the weighting device, and correct and easy adjustment of pressure for a selected staple of fibers to be processed.

A lever having a fulcrum on the loading rod at a point at the far side of the fixed abutment on the machine frame from the spring is provided with a cam surface which is used to lift the loading rod with respect to the abutment and in so doing serves to transmit the spring load wholly to the cylindrical cover or shield through which normally the spring thrust is delivered to the abutment, thereby unweighting the pair of rolls involved by removing the spring load from the weighting members which normally transmit the spring load to the ends of the top roll. Since this also takes the spring load off of the abutment on the machine frame, it permits the shift of the pairs of rolls in changing the roll setting without loss of the adjustment of the weighting of the respective pairs of rolls, which initial weighting is re-established when the lever is moved reversely to let the spring load again fall on the abutment on the machine frame. The load transmitting members are made in the form of a pair of hooks engaging the bearings at the respective ends of each top roll, and having a lost-motion and thus loose connection of each hook to its respective end of the equalizing beam, with auxiliary springs lifting the equalizing beam and loading rod and the parts carried thereby upward along the shanks of the hooks, thereby leaving the entire weighting system of each pair of rolls pendant therefrom to follow the lateral movement of such rolls in changing the roll setting, whenever the lever is moved to unweight the rolls by taking the thrust of the loading spring off of the abutment. This construction incidentally also permits the levers to be in a normally out-of-the-way position during operation of the draw box. The extremity of the bent end of each hook applies the pressure at the center line of the bearing blocks at the ends of the roll, thereby providing center-point loading and permitting easy removal of the top roll even when the hooks are lifted only a relatively short distance. By fitting the hooks slidably in grooves at the ends of the mounting blocks of each pair of rolls and providing a guide at these grooves, further assurance of loading at the proper point of the top rolls is obtained.

These and other objects, features, and advantages of the invention will become more apparent from the following description taken in connection with the accompanying drawings showing a preferred embodiment of the invention and wherein:

Fig. 1 is a partially sectionalized end elevation of a draw box and weighting arrangement as seen from the delivery end of the draw box.

Fig. 2 is a side elevation with one side-plate partly broken away to show the construction more clearly.

Fig. 3 is a plan view with the top rolls and bearings removed.

Fig. 4 is a view mainly in vertical section detailing the mounting of a pair of draw rolls.

Referring to Figs. 1 and 2, a weighting coil spring 10 enclosed in a cylindrical and expansion-limiting shield 12 having end portions 14 crimped inwardly is compressed between an upper washer 16 and lower washer 18. The compression load

of the weighting spring 10 is transmitted at its upper end through the washer 16 and the upper crimped portion 14 of the shield 12 to an abutment comprised by two horizontal bars 19 rigidly fixed in place on frame member 20 of a draw box 22 by screws 24. The compression load of the weighting spring 10 is transmitted at its lower end through the washer 18 and a stop 26, such as a threaded nut, to a loading rod 28. The lower end of the loading rod 28 has a threaded portion 30 to permit adjustment of the stop nut 26 so as to control the degree of compression of spring 10 and thereby the load on loading rod 28. Trial and error loading of the loading rod 28 may be removed by providing calibration marks 32 on the stop nut 26. The calibration marks 32 are spaced preferably for equal fine increments of load and may be read with the bottom crimped portion 14 of shield 12 as a reference. The crimped portions 14 and washers 16 and 18 confine the weighting spring 10 to a maximum axial extension determined by the distance between the crimped portions 14. When the lower washer 18 is just raised by the stop nut 26 above the bottom crimped portion 14 as shown in Fig. 1, the weighting spring 10 is producing its minimum load on loading rod 28. This point may be designated by alignment of the top calibration mark of the marks 32 with the lower crimped portion 14 of the shield 12 as shown in Fig. 1.

A locking nut 34 may be provided for locking the stop nut 26 in place after a proper adjustment has been made.

The load from weighting spring 10 on loading rod 28, which extends slidably through a central hole in a bushing 38 having a rounded flange supported by bars 19, is transmitted by the loading rod 28 through a member 38 termed the lift adjuster (for reasons given later herein) to the center of a load equalizing beam 40. The lift adjuster 38 is screwed onto the threaded upper end 44 of loading rod 28 and mounted with a sliding fit in a hole in beam 40, being retained therein by a flat head on its upper end and a washer 48 of larger diameter than body portion 42 which is held against the lower end of portion 42 by lock nut 46. Flats are milled on the lower side portions of body 42 for the purpose of applying a wrench to turn this member to screw it up or down on rod 28.

To transmit the loading thus applied to the equalizing beam 40 by weighting spring 10 equally to the two hooks 60 associated therewith, beam 40 is provided at its ends with hubs 41 having holes therethrough parallel to and equidistant from the axis of loading rod 28, in which slide freely the upper portions 51 of bushings 54 mounted on the threaded lower ends 62 of the hooks 60. The lower portion 52 of each bushing 54 is of greater diameter than the upper portion 51, and on the shoulder formed at the junction of these two different outside diameters rests a washer 56 engaging the under surface of hub 41. The bottom of the bushing 54 rests on a second washer 58 which is supported from below by a stop nut 59 and lock nut 60 on threaded portion 62. Through this bushing the downward pull of equalizing beam 40 is delivered equally to the two hooks 60 associated therewith. Nuts 59 and 60 clamp the bushing in position between washers 56 and 58 and provide adjusting means for leveling equalizing beam 40. Leveling of the equalizing beam centralizes the T-shaped bushing 38 between the fixed support bars 19, preventing binding of the loading

rod 28 and preventing unequal loading of the two hooks 60. Bushings 52 also protect the threads on the ends 62 of hooks 60 from chafing in the ends of equalizing beam 40.

The load from weighting spring 10 is evenly distributed by the load equalizing beam 40 between its pair of hooks 60 since the lift adjuster 38 is in a position midway between hooks 60. These equal loads on the two hooks 60 are transmitted, through the free ends 64 of hook-shaped end portions 66 (Figs. 2 and 4), forming the upper ends of the hooks 60, to support-blocks 68 for top rolls 70 in a downwardly direction at the vertical center line 72 (Fig. 2) running through the axis of the top rolls 70. The equal loads from each member of the pair of hooks 60 on the support-blocks 68 are transmitted through bearings such as ball bearing sets 74 to the pintles 76 of top rolls 70. Because of clearance 78 (Figs. 1, 2 and 4) between support-blocks 68 and mounting-blocks 80, the equal loads at top roll ends 76 result in a pressure which is equal and uniform throughout the length of the line of contact 82 between top roll 70, in this instance having a resilient covering 83 (Fig. 4) such as rubber or cork, and bottom roll 84 which is firmly mounted in place by its ends 86 in bearings such as ball bearing sets 88 held in mounting-blocks 80.

A lever 90 having a handle 92 at one end and a forked construction at the other end with parallel cam surfaces 94 and straddling the loading rod 28 is provided with a fulcrum on the loading rod 28 at a point between the equalizing beam 40 and the abutment formed by the rigidly fixed bars 19 on the machine frame 20. The fulcrum consists of a pivot member 96 such as a bolt in holes through both lever 90 and loading rod 28 and having aligned axes perpendicular to the axis of the loading rod 28.

In normal operating position the lever 90 will be down, with the handle 92 pointing downward in an out-of-the-way position beneath the draw box 22 as shown in Fig. 1. In this position a space 98 will exist between the cam surface 94 of lever 90 and the top of the bushing 36. In this position of lever 90, the full load from weighting spring 10 will be transmitted to the top roll 70.

When the handle 92 of the lever is raised the high portion 102 of the cam surface 94 impinges against the top of bushing 36 forcing the latter downward slightly and causing the pivot member 96 to move the loading rod 28 upward, compressing loading spring 10 and raising lift adjuster 38, thus unweighting the equalizing beam 40. This permits beam 40 to rise under the upward pressure of expanding coil springs 110 surrounding the lower portion 52 of each bushing 54 and confined between washers 50 and 56, the lesser-diameter upper portions 51 of bushings 54 being as noted arranged with a free fit in the holes at the ends of the equalizing beam 40. Therefore as loading rod 28 moves upward the equalizing beam 40 being urged by springs 110 slides upward relative to the bushings 54, stopping before encountering washers 106 backed up by stops 108. The stops 108 are nuts screwed onto the threaded portions 62 of hooks 60 and locked in place by lock nuts 109.

The springs 110 expand as the equalizing beam 40 moves upward and hold the hook portions 66 of hooks 60 firmly but yieldingly in place on support blocks 68. The upward movement of the equalizing beam 40 is controlled by the amount of lift at the cam surface 102, and the adjustment of

the threaded portion 44 of loading rod 28 in the lift adjuster 38. The latter is the primary point of adjustment for providing the correct rise of the equalizing beam 40 to a position short of contact with washers 106. When handle 92 of lever 90 is in its raised position, and the equalizing beam 40 is in its raised position, the upper ends 66 of hooks 60 can be moved inward off the support blocks 68 manually against the pressure of springs 110 and rotated a quarter turn on their axes to provide clearance for the removal of the top roll 70 with its support blocks 68. The hooks 60, when not supported by support blocks 68, move downward until washers 106 bear against the top of equalizing beam 40, which, in turn, is stopped from moving downward by washer 48, loading rod 28, cam 94, and bushing 36 bearing on fixed support bars 19.

When as stated lever 90 is in raised, unloaded position, the main loading spring 10 exerts no pressure against any part of the draw box frame or rolls. This is so because the raising of lever 90 into its unloading position causes its cam surface 102 to intervene rigidly between the pivot point 96 and bushing 36, and thus to create a self-contained, stable, balanced system of forces (tension and compression) between the two ends of the system, namely, pivot point 96 and stop nut 26. This system exerts no force against any point outside it due to loading spring 10, although the weight of its parts of course is supported through the upper end of rod 28 and beam 40 by hooks 60 when they are in place on support blocks 68. When hooks 60 are removed from support blocks 68 for removal of top roll 70, as described above, the weight of all the parts is then supported by the flange of bushing 36 resting on bars 19. In this raised, unloading position of lever 90 the closed system of forces which contains loading spring 10 has as its tension member the rod 28, between pivot point 96 and stop nut 26. Its compression members are: the cam portion of lever 90 between pivot point 96 and cam surface 102 which presses on bushing 36, which presses in turn on the upper crimped portion of shield 12, which presses through washer 16 on compressed loading spring 10, which then presses through washer 18 on stop nut 26 fixed at the lower end of rod 28, thus closing and balancing the load system and effectively removing all but the weight of the parts from any reaction against the frame or rolls.

The shield 12, as such, plays no part in this closed system of forces, but is merely suspended from its upper crimped portion which is firmly held between the lower surface of bushing 36 and the upper end of loading spring 10 acting through washer 16; the lower end of spring 10 bears against stop nut 26 through washer 18, and not against the lower crimped portion of shield 12. Shield 12, as referred to elsewhere, serves to provide a predetermined minimum compression of spring 10; its lower crimped portion is a convenient reference for adjusting calibrated stop nut 26, and it provides a convenient package for containing the loading spring 10 during disassembly.

By using the free end 64 of each hook 60 as the load transmitting point instead of the whole curved portion 66 of the hook, not only is pure vertical loading insured but also the necessary upward travel distance may be shortened and still permit removal of the top roll 70 and its support blocks 68, thereby permitting compactness of construction.

Flat sides 111 (Fig. 2) are provided at the cir-

cumferential recess 112 (Fig. 4) about the periphery of the support blocks 68. The flat sides 111 fit slidably between upright yoke members or fingers 114 formed on the top of mounting blocks 80, thereby keeping the top roll 70 in proper alignment with the bottom roll 84 and preventing rotation of support blocks 68 and further insuring stable vertical loading by the hook ends 64.

Additionally, a guide 116, Fig. 2, is fixed in a slot in each mounting block 80 having a hole receiving the shank of each hook 60 and permitting axial sliding motion of the hook along the left side of mounting block 80, thereby helping to maintain the end 64 of hooked portion 66 at the center line 72 of the top roll 70.

Each pair of mounting blocks 80 is clamped in place against a rigid base 118 by a rod 120 and nut fastening 122. The rigid base 118 is itself fixed in place on the frame member 20 by screws 123. While not limited thereto, in the embodiment there are four pairs of mounting blocks 80, each mounting a pair of draw rolls weighted as described above and a pair of mounting blocks appearing second from the right in Fig. 2 are immovably fixed in place. The other three sets of mounting blocks with their corresponding weighted rolls, each have rack teeth 124 at their bottom ends meshing with the teeth on a corresponding pinion 126 having a squared end 128. By loosening nut 122 on the end of clamping rod 120 and turning the squared end 128, a corresponding pair of mounting blocks 80 may be moved to the left or right on guides 129, thereby permitting adjustment of the distance between axes of adjacent pairs of draw rolls for a particular staple of fiber to be processed by draw box 22. A slot 130 (Fig. 2) is provided in side plate 132 to accommodate the lateral movement of the nuts 122 in this adjustment. Grooves 134 (Fig. 3) on both sides of mounting blocks 80 and recesses 136 (Fig. 2) receive the hooks 60 and guides 116 respectively. This mechanism for setting the rolls forms no part of the present invention.

It should be noted that when such adjustment is to be made, lever 98 is raised, and thereafter hooks 60, equalizing beam 46, and loading rod 28, with weighting spring 10, will move laterally together with the mounting blocks 80, pendent therefrom and thus in proper alignment therewith along a vertical plane. There is no binding against the rigid support bars 19, because when the handle 92 of the lever 98 is raised and hooks 60 are supported by support blocks 68, the combined weight of equalizing beam 46, lift adjuster 38, loading rod 28, lever 98, bushing 36, spring 10, and shield 12, is supported by springs 110. Bushing 36, having its sleeve portion longer than the vertical thickness of bars 19, becomes a spacer delivering the thrust of cam 94 directly to the top of shield 12, thus depressing the latter and relieving the normal pressure of the shield upward against bars 19.

Adjustment to compensate for roll wear is made by screwing the lift adjuster 38 farther down on loading rod 28, fixing it by locknut 46. Adjustment for roll wear may alternatively be made by moving pairs of nuts 58 and 108 and the intervening bushings 54 on both sides upward equally, so long as the available length of hooks 60 and of the threaded lower ends 62 thereof are adequate for the required amount of adjustment; but the lift adjuster 38 is the principal means for obtaining this adjustment, because simpler.

The draw bar 22 also incorporates an under-clearer 134 contacting the bottom rolls 84 and mounted on a slide 136 with the handle 138 and mounted for proper upward wiping pressure on springs 140 fastened to the rigid base 118 by screws 142.

A condensing guide 144, Figs. 2 and 3, is interposed between the second and third pairs of rolls in the draw box, being mounted in a vertical plane on supports 146 resting on adjacent pairs of support blocks 80. This guide is slotted horizontally throughout the major portion of its width, with tongues 148 extending obliquely toward the nip of the succeeding pair of drawing rolls to gather in the lateral edge of the fleece or sliver being drawn in the draw box.

This invention is not limited to the particular details of construction and operation herein described, as equivalents will suggest themselves to those skilled in the art. It is accordingly desired that the appended claims be given a broad interpretation commensurate with the scope of the invention within the art.

What I claim is:

1. Weighting means for the top rolls of a draw box operating on textile fibers comprising in combination a load-transmitting member weighting each end of a top roll, a beam transmitting a load to said members, a loading rod having one end held to said beam at a point midway between said members, an adjustable stop at the other end of said rod, graduations on said stop for selectively setting said adjustment, a fixed abutment, means thereon providing an index reading against such graduations, and a spring loading said rod compressed between said abutment and the stop and exerting pressure against said stop to a degree controlled by the adjustment of said stop, thereby providing selective equalized loading of said top roll.

2. Weighting means for the top rolls of a draw box operating on textile fibers comprising in combination a hook suspended from each end of a top roll, a loose load-equalizing member in load transmitting engagement with said hooks, an abutment, spring means reacting against the abutment producing a load on said member at a point between the hooks, and lever means in cooperative relation to said spring means removing the load from the member by further stressing the spring means and preventing its reaction against the abutment.

3. Weighting means for the top rolls of a draw box operating on textile fibers comprising in combination a load-transmitting member weighting each end of a top roll, a beam transmitting a load to said members, a loading rod having one end held to said beam at a point intermediate said members, a stop at the other end of said rod, fixed support means at said rod between said stop and said beam, a spring loading said beam and compressed between said stop and said support means, and a lever disposed to selectively apply and remove from said load-transmitting members the load of said spring.

4. Weighting means for the top rolls of a draw box operating on textile fibers comprising in combination a load-transmitting member weighting each end of a top roll, a beam transmitting a load to the members, a loading rod having one end held to the beam at a point intermediate the members, a stop at the other end of the rod, fixed support means at the rod between the stop and the beam, a spring loading the beam and compressed between the stop and the support means,

and a lever having a fulcrum on the rod and adapted to lift the rod, thereby removing from the load-transmitting members the load of the spring.

5. Weighting means for the top rolls of a draw box operating on textile fibers comprising in combination a load-transmitting member weighting each end of a top roll, a beam transmitting the load to such members, a loading rod having one end held to the beam at a point intermediate the members, a removable stop at the other end of the rod, fixed support means at the rod between the stop and the beam, a spring on the rod compressed against the stop and the support means, and a hollow cylinder housing the spring and having portions at both ends limiting the spring's extensions.

6. Weighting means for the top rolls of a draw box for drawing textile fibers having in combination a hook suspended at its upper end from each end of a top roll, a load-equalizing member having a passage at each end through which the shank of one of the hooks extends, stops on the shank of each hook spaced apart to allow limited axial movement of the shank in the passage, means loading the equalizing member and the hooks, and a spring reacting against the equalizing member and one stop on each hook to urge the other stop thereon toward such member.

7. Roll weighting means for a draw box operating on textile fibers comprising in combination a hook weighting each end of a roll and having a portion of its shank threaded, means on the threaded portion in spaced relation to each other and defining an adjustable top and bottom stop on each hook, a load-equalizing beam transverse to the shanks and having holes slidably fitting the shanks between the stops, a spring surrounding the shank of each hook between the stops, a loading rod having one end held to said beam at a point midway between said hooks, an adjusting nut at the other end of said loading rod, a fixed abutment, a spring on said loading rod compressed between the abutment and the nut by an amount controlled by such nut, and a lever having a fulcrum on the loading rod and adapted to lift such loading rod and relieve the spring's pressure against the abutment.

8. Roll weighting means for a draw box operating on textile fibers comprising in combination a hook in load-applying relation with each end of a roll and having a threaded shank, means on the threaded shank of each of the hooks and in spaced relation to each other and defining an adjustable top and bottom stop on each of the hooks, a load-equalizing beam transverse to the shanks and having holes slidably fitting around the shanks between said stops, a spring on each shank urging the beam toward the top stop, a loading rod having one end held to the beam at a point intermediate the hooks, an adjusting nut at the other end of the loading rod, fixed support means at said rod between the nut and the beam, a spring on the loading rod compressed against such adjusting nut and the fixed support means, and a lever having a fulcrum on the loading rod and a cam surface engaging a surface in connection with the fixed support means to lift the loading rod with respect to the support means.

9. Roll weighting means for a draw box operating on textile fibers, having in combination hooks each weighting one end of a roll by engage-

ment with parts on the end of the latter, a bar connecting the hooks, an abutment, spring means reacting against such abutment loading the bar, and lever means applying additional stress to the spring means preventing its reaction against the abutment thus relieving the load on the bar and unweighting the hooks.

10. Roll weighting means for a draw box operating on textile fibers, having in combination hooks each weighting one end of a roll by engagement with parts on the end of the latter, a bar connecting the hooks, spring means including a tension element acting on both ends of the spring and loading the bar, and lever means movable in one direction to further stress the spring means to remove the spring load from the bar, and in the other direction to restore the initial spring load to the bar.

11. Roll weighting means for a draw box operating on textile fibers, having in combination means transmitting and equalizing the weighting force applied to the two ends of a roll, and weighting means employing a loaded spring and a tension element and adapted both to exert force upon the first means so as to effect the weighting of the roll and alternatively to be self-contained and free the roll from the weighting force of the spring by confining the spring's entire force to the tension element.

12. Roll weighting means for a draw box operating on textile fibers, having in combination means transmitting and equalizing the weighting force applied to the two ends of a roll, an abutment, a spring reacting thereagainst and normally creating the weighting force, and means loading the spring and relieving the force applied to the abutment by the spring.

13. Roll weighting means for a draw box operating on textile fibers, having in combination a spring normally creating a weighting force, means including a tension element transmitting the weighting force to the ends of a roll, and means on the tension element optionally taking the force of both ends of the spring and thereby relieving the load on the roll.

14. Roll weighting means for a draw box operating on textile fibers, having in combination a spring normally creating a weighting force, means including a tension element transmitting the weighting force to the ends of a roll, and means on the tension element optionally connecting first one end and alternatively both ends of the spring to the tension element to weight and unweight the roll, respectively.
